PROCESS FOR PRINTING AND DECORATING
FABRICSRobert Stutz, Arlington, N. J., assignor to S. T. &
S. Holding Co. Inc., New York, N. Y., a corpora-
tion of New York

Application June 18, 1940, Serial No. 341,103

6 Claims. (Cl. 101—211)

The present invention relates to a method and means for decorating textile fabrics and particularly relates to a method and means of decorating textile fabrics upon which or to which are to be applied multi-colored designs.

It is among the particular objects of the present invention to provide an improved apparatus of the character described which will apply to fabrics multi-colored designs with assurance that said designs will not tend to run into each other 10 or become smeared, with a high speed of production.

Another object is to provide an improved method and means of printing textile fabrics or other fabrics in sheet form which will involve relatively few parts and which will be simple and convenient to manufacture.

Another object of the present invention is to provide an improved printing plate construction which may be utilized for decorating fabrics and 20 obtaining multi-colored prints of various designs on fabrics and particularly on woven textile fabrics.

Still further objects and advantages will appear from the more detailed description set forth below, it being understood, however, that this more detailed description is given by way of illustration since various changes therein may be made by those skilled in the art without departing from the scope and spirit of the invention.

In accomplishing the above objects, it has been found most satisfactory to cause the fabrics in being printed or decorated to be carried upon a roller or carrier face which will apply the necessary decorating or printing material thereto.

In the preferred form of the invention, means are provided to hold the fabric closely in contact with said roller, a carrier or presser belt being utilized in one form of the invention, which belt, at the same time, is pressed downwardly, pressing the fabric downwardly upon the imprinting surface by an adjustable weighting means.

If desired, the fabric may be conveniently moistened before being carried upon the imprinting rollers, and after being imprinted, the 45 fabric may be conveniently wound upon a roller or placed upon a flat rolling means with or without interspacing or separating materials.

In forming the printing plate or printing cylinder, it has been found most satisfactory to form a doughy mass consisting of a water soluble material, with which may be combined the coloring composition either in the form of a pigment or dye, a hygroscopic agent and a dispersing or emulsifying agent.

The material should be of such a nature as will dry out in air to a relatively hard coherent, non-brittle, non-friable, although plastic mass, yet which when moistened will become sufficiently plastic that a top surface of it may be picked up by a fabric pressed in contact with it.

At the same time, the printing mass which may be placed upon a plate or cylinder, should retain its body and structure without tending to crack or become detached from the base, when dried or when moistened preparatory to printing or when actually used in printing.

Among the water soluble materials which may be employed are gelatine, pectin, gum arabic, gum tragacanth, British gum, dextrine, gum shiraz, locust bean gum, agar agar, glue and other types of water soluble or water absorbent mucilages, gums or colloids.

The proportion of colloids to water should always be such that there will be a heavy doughy mass which may be readily kneaded and stretched without breaking and having the plasticity and texture substantially that of a well-aged bread dough.

Depending upon the particular colloid, gum or mucilage, it is desired to employ, it has been found that from 50 to 90% of the colloid will sufficiently body the water to form the desired mixture.

As a general rule, it has been found most satisfactory to use colloids, gums, or mucilages other than starch which may be readily converted into a doughy or plastic mass with starch.

To preserve the material, it has been found most satisfactory to add small amounts of hydroxylated benzenes or naphthalenes, such as phenols, or hydroxy napthenes or carboxylic acids such as benzoic acid or even inorganic acid such as boric acid, the amounts of these agents varying from about $\frac{1}{2}$ to 2%.

To regulate the water absorptive qualities of the mixture, it is also possible to include small amounts, say from 1 to 10% of poly-hydroxy-alcohols, such as ethylene glycol, propylene glycol, glycerol, sorbitol, mannitol, cellosolve, carbitol, or less preferably, sugar.

It is also possible to include various combinations including alkanol amines such as mono, di and triethanolamines, diamino propanol, isobutanol, which may also be converted into dispersing or surface active agents by combination with fatty acids such as stearic acid, oleic acid, linoleic acid, coconut oil fatty acids, eruric acid, elaidic acid, ricinoleic acid, eleostearic acid,

palmitic acid or lauric acid with or without heating and pressure.

As dispersing or surface active agents, it is also possible to include various amido, amino, boric, phospho, or sulpho derivatives of aliphatic compounds having from 12 to 26 carbon atoms, such for example, as sodium lauryl sulphate or sulphonate, stearic triethylene amide, the ethyl ester of sulphonated oleyl alcohol, phosphates and borates of lauryl and myricyl alcohol, and so forth.

These surface active agents are generally utilized in amounts varying from 1 to 5%.

The pigment or dye which is utilized, depending upon the type of fabric which is to be printed or decorated, may be widely varied.

Referring to the drawings which illustrate one of the various possible embodiments of the present invention, but to which the present invention is by no means restricted since the drawings are merely by way of illustration and not by way of limitation,

Figure 1 is a diagrammatic side elevational view of a mechanism according to one embodiment of the present invention.

Figures 2 and 3 are respectively detailed side sectional views of the imprinting roller and the wind-up roller.

Figure 4 illustrates an alternative mechanism for printing the fabric in diagrammatic side sectional view.

Figures 5 to 13 illustrate one method of forming a printing plate, each of the figures being a perspective view illustrating successive steps in combining the doughy or plastic mass together to form the final printing plate, Figures 5 and 6 illustrating the formation of the base element; Figures 7 to 11 illustrating the treatment of this base element to form the composite design elements; Figure 12 illustrating a series of the elements prior to application to a circular printing roller and Figure 13 being a perspective view of the elements as applied to a circular printing roller.

Figures 14 to 16 illustrate still another embodiment in which the printing element consists of a felt or rubber cover, portions of which have been cut out to receive the coloring masses; Figure 14 being a side elevational view and Figures 15 and 16 being sectional views upon the line 15-15 of Figure 14 upon enlarged scale as compared to Figure 14 illustrating the construction of the cylinder before and after the application of the covering mass.

Figures 17 to 19 illustrate another alternative procedure for forming the printing cylinder, Figures 17 and 19 being side elevational views of ends of the roller, respectively, before and after the design has been placed therein and after certain portions have been cut out, and Figures 18 and 20 being respectively side sectional views upon the lines 18-18 and 20-20 of Figures 17 and 19.

Referring to Figures 1 to 3, the frame of the machine A is provided with the vertical members 10, and the cross members 11, 12 and 13.

The fabric B to be imprinted, is carried before imprinting upon the roller C, is passed over the printing roller or decorating roller D and on to the wind-up device E.

The roller C has the trunnions 14 which are carried by the bearing structure 15 on the cross-bar 11.

The fabric moves in the direction of the arrow 16, over the guide roller 17. The guide roller 17

has the trunnions 18 which are carried by the bearing structure 19, said bearing structure 19 being mounted on the cross-bar 12.

The fabric B then passes under the stretching roller or cylinder 20 carried by the structure 21. The structure 21 is mounted on the vertical frame member 22. The fabric B then passes over the main roller D. This roller D, as is better shown in Figure 2, has the central pivot element 33, the structural center 24, and the imprinting face 25 which may be, if desired, of a soluble material which will gradually be dissolved off on the fabric B.

Pressing the fabric B against the imprinting face 25 is the belt or fabric covered element F which unwinds from a roller 26 having its trunnions 27 bearing in the mount 28 in the side beam member 10.

This belt passes over the roller D closely pressing the fabric B against such roller, as best indicated in Figure 2.

Pressing the fabric B and the belt F against the portion 25 of the roller D are the rollers 29, 30 and 31 and 32 which are held by the frame work G consisting of the upstanding members 33 and the cross-bar 34.

These rollers 29 to 31 are of predetermined weight so as properly to press the fabrics F and B against the face 25 of the roller D.

After passing over the roller D, the belt F is passed onto the roller H which has the bearing structure 35 in which trunnions 36 of the roller are carried.

The imprinted fabric B is then passed onto the take-up device E which, as is best shown in Figure 3, has the side members 37, the end bars 38 upon which the fabric is wound, and the pivotal center member 39.

The device E rotates in the direction indicated by the arrow 40 in Figure 3.

From the roller 41 having the bearing 42 carrying the trunnions 43, is drawn the spacer or paper 44 which is spaced between the imprinted fabric F as it is wound upon the bars 38.

The roller H is driven by the pulley 47 by the belt 45 from the pulley 46. The pulley 46 is driven from the gear box 48. The gear box 48 is driven from the pulleys 49 and 50 through the belt 51. The motor 52 drives the pulley 50. The motor 52 is mounted at 53 upon the floor 54. The wrapping up device E is driven from the pulley 55 through the cross belt 56 which is driven from the pulley 41.

It will be noted that both the fabric B and belt F are pulled through the machine by the rollers H and the wrapping up device E.

Where it is desired to moisten the fabric or to feed a moistening sheet against the fabric at the side thereof away from the side which contacts the roller D, the sheet B', may be fed by the rollers 57 through the box 58 where it is suitably moistened or picks up a solvent which will moisten and dissolve the surface of the material 25, as shown in Figure 2.

After passage through the box 58, the material will pass through the rollers 59 and over the rollers 61.

To lift part or all of the pressure rollers 29 to 31, and thus regulate the pressure in the main printing roller D, the lever apparatus I is provided having a pivot mount at 60 on the upstanding bar 61 extending upwardly from the frame member 13.

The left end 62 of the bar would lift the end of

the rollers which project beyond the gauge G and enables the weight to be adjusted or the pressure rollers to be removed.

The right end of the bar 62 is connected at the pivot point 64 to the handle member 65 which may be actuated at 66. The openings 67 enable adjustment in the positioning of the lever 65 and the bars 62, 63.

In operation, the fabric will pass in the direction 18 from the roller C to the roller E and the belt F will move in the same direction.

The pressure rollers 28 to 32 will turn in contact with the belt F as it passes over the roller B.

The belt F and the fabric B again will separate to be taken up separately on the devices H and E.

In the alternative construction shown in Figure 4, there is a frame work 74 having the upright members 75 and 76, and the cross members 77, 78 and 79 which may consist of channel irons.

The upright members 75 and 76 carry the hook members 80, 81 and 82, the hook 80 serving as a bearing for the feed roller 81 carrying the silk or fabric 86 to be imprinted and the hook member 82 carrying the shaft 83 for the roller 84 carrying the contact sheet or pressure sheet 85.

The cross members 78 also carries the bearing 87 for the temple member 88 which stretches out the fabric to be imprinted. Both the fabric 86 to be imprinted and the covering cloth 85 come together at the printing roller 89, the shaft 90 of which has a bearing 91 on the upper cross member 79.

The vertical member 74 has an extension 92 carrying the pivot 93 for the bar 94. From the upper end of the extension 92 extends the cross bar 95 having the two dependent members 96 forming a slot 97 in which fit the trunnions or shafts 98 of the pressure rollers 99.

The lower trunnion 98 is positioned above the extension 100 of the arm 94. The lower pressure roller 99 presses down upon the printing roller 89 pressing the silk sheet 86 against the printing roller 89 through the intermediate sheet 85.

The other end 101 of the arm 94 is connected to the rope or chain 102 passing over the pulleys 103, 104 and 105 to the handle 106 which may be drawn downwardly to lift the pressure of the rollers 99 to the printing roller 89. The pulley 103 is mounted on the roof 116 of the chamber 117 having an inlet opening 118 and an outlet opening 119 for the fabric.

The pulleys 104, 105 are suspended from the ceiling 107 as is also the cage 108. The floor 109 of the cage 108 receives the motor 110 and the gear box 111. The gear box 111 has a wheel 112 driving the chain 113 which in turn drives the gears 114 and 115 and the take up roll 123 for the backing fabric 85.

The roll 123 has a shaft 120 carried in the bearing 121, which is mounted upon the extension 122 of the top bar or frame member 79.

The silk 86 after being printed passes through the opening 118 in the drying chamber 117 over the rollers 124, 125 having the shafts 194, 195 and out through the outlet 119 on to the rollers 126, 127 and finally over the driven roller 128.

The gear 115 drives a pulley carrying the belt or chain 190 which drives the pulley 191 having the bearing 192 in the standard 193.

From the roller 128 the printed fabric 129 drops into the box 130, where the goods having been imprinted folds itself up, as indicated at 131, and is ready to be boiled off or otherwise finished.

In the drying chamber 117 there is positioned

a motor 132 for driving the fan 133, sending out the blast of hot air 134. The fan is provided with a radiator, not shown, supplied with a heating fluid through the pipe 135.

Both the fabrics 85 and 86 may be moistened before imprinting and preferably the moisture of the printing roller 89 should be increased by water sprays or by steaming, so that imprinting will readily take place.

If desired, a cage apparatus, such as indicated at 33 and an adjustable device, such as indicated at 65 in Figure 1, might also be used in connection with the construction of Figure 4.

It is thus apparent the applicant has provided a simple, inexpensive apparatus for the improvement of fabrics which may be widely applied whether or not the fabric is moistened and which is subject to wide utilization.

In forming the printing roller, the plastic material, together with the coloring matter may be prepared in a series of kneadable doughs having different color values.

As shown in Figure 5, there is a round or cylindrical mass 150 formed of one color, red or blue, which is laid upon a contrasting colored sheet 151 which may be white.

Then, the sheet 151 is wrapped around the cylindrical mass 150, as indicated in Figure 6, with the ends of the sheet meeting at 152. The mass, as shown in Figure 6 is then stretched out into a thinner mass, as indicated at 153 (Figure 7) by the hands 154 and then the drawn out mass is cut by the hot knife 155 to form the segments 156.

The segments 156 are then laid together, as indicated in Figure 9, together with the triangular or prismatic spacer elements or blanks or negatives 157, which fill the interstices between the cylindrical masses 156.

Then, the mass at Figure 9 is drawn out to form a series of masses 158 which again are then laid together six at a time, as indicated at Figure 11, together with the intermediate spacers or filler members 159. The mass of Figure 11 is then drawn out and is finally cut up to form the segments 160 which may then be placed in position, as indicated in Figure 13, upon the face 161 of the printing roller having the shaft 162.

The method of making the plate, as set forth in Figures 5 to 13, is, of course, illustrative and many changes could be made in this method to give widely varying different designs or constructions as the case may be.

In respect to Figures 14 to 16, the basic printing roller 165 is covered with felt 166 which has cut out portions 167. These cut-out portions then may be filled with specimens of the doughy mass 168, as shown in Figure 16.

By making the felt 166 of suitable waterproof material which is compressible so as to permit contact even though the mass 168 be dissolved or largely used up, it is possible to obtain a series of designs from the mass 168 without interference of the felt 166.

In the arrangement shown in Figures 17 and 18, the roller 170 is provided with a rubber cover 171 upon which is placed a lacquer or varnish forming a pattern 172.

This varnish is preferably oiled or waxed so that none of the imprinting material will flow thereon and if desired, a doctor plate, not shown, may be used thereon.

Then, the unpainted or unvarnished portions may be cut out, as indicated at 173 in Figure 19, and these recesses may then be filled by a printing mass or masses 174.

The rubber should have sufficient pliability so that as the printing mass 174 is consumed there will be satisfactory contact between the printing mass and the fabric being imprinted.

Although the printing roller is preferably used for textiles, it may also be used for printing other flexible sheet materials.

It is apparent the specific illustrations shown above have been given by way of illustration and not by way of limitation and that the structures above described are subject to wide variation and modification without departing from the scope or intent of the invention all of which variations and modifications are to be included within the scope of the present invention.

The word "body" as used in the specification is meant a water soluble gum or gelatinous material which has the property of taking of water and forming a paste, jelly or gummy mass, and thus decrease the liquidity and increase the viscosity of the mixture.

What is claimed is:

1. The method of making printing plates and rollers comprising forming water soluble doughy masses of different colors, stretching them into cylinders, cutting up the cylinders, laying them together, repeating the stretching, cutting and laying operations and then placing the segments on a base.

2. The method of making printing plates and rollers comprising forming water soluble doughy masses of different colors, stretching them into cylinders, cutting up the cylinders, laying them together, repeating the stretching, cutting and

laying operations and then placing the segments on a base, said mass comprising water soluble materials.

3. The method of making printing plates and rollers comprising forming water soluble doughy masses of different colors, stretching them into cylinders, cutting up the cylinders, laying them together, repeating the stretching, cutting and laying operations and then placing the segments on a base, said mass comprising water soluble materials and emulsifying agents.

4. The method of making printing plates and rollers comprising forming water soluble doughy masses of different colors, stretching them into cylinders, cutting up the cylinders, laying them together, repeating the stretching, cutting and laying operations and then placing the segments on a base, said mass comprising water soluble materials and hygroscopic agents.

5. The method of making printing plates and rollers comprising forming water soluble doughy masses of different colors, stretching them into cylinders, cutting up the cylinders, laying them together, repeating the stretching, cutting and laying operations and then placing the segments on a base, said mass containing a combination of dextrin and water.

6. A method of making a printing plate which comprises forming a stretchable dough of a coloring material, a water absorbent material, a hygroscopic agent and a dispersing agent and forming colored designs therefrom.

ROBERT STUTZ.
